SEAMING HEAD AND MOUNTING THEREON

Alfred L. Kronquest and Otto A. Schmitt, Syracuse, N. Y., assignors to Continental Can Company, Inc., New York, N. Y., a corporation of New York

Original application November 27, 1939, Serial No. 306,366. Divided and this application September 15, 1941, Serial No. 410,948

10 Claims. (Cl. 113—24)

The invention relates generally to can making machinery and more particularly to container and end closure assembling machines of the nature disclosed in the co-pending application for U. S. Letters Patent filed by Otto A. Schmitt on Nov. 10, 1939, Serial No. 303,991, and it primarily seeks to provide a novel seaming head structure for use in a machine of this character and a novel mounting therefor. This application is a division of the previously co-pending application for U. S. Letters Patent filed by Alfred L. Kronquest and Otto A. Schmitt on Nov. 27, 1939, Serial No. 306,366 and entitled Square can seaming head, now Patent 2,271,153, issued January 27, 1942.

In the can and end closure assembling machine disclosed in the co-pending application for U. S. Letters Patent above referred to, the can bodies and end closures are individually fed to a turret which is indexed about a horizontal axis, and means are provided on and in cooperative relation to the turret for presenting the can bodies and end closures in loosely assembled relation at a seaming station at which the end closures are seam-secured upon the can bodies. It is the purpose of the present invention to provide a novel arrangement of seaming head disposed in cooperative relation to the turret and on a horizontal axis, and a novel mounting for said head which will enable it to be readily swung away from the turret from its operative position to an ineffective position so as to facilitate servicing or inspection of the turret or the seaming head parts.

An object of the invention is to provide a seaming head of the character stated which is swingable away from the turret about a vertical axis, and novel driving connections for the operating parts of the head which will not be disrupted by movement of the head about its pivotal mounting.

Another object of the invention is to provide novel means other than the pivotal mounting of the head for supporting the weight of the head while it is being swung into or out of its cooperative relation with the turret.

Another object of the invention is to provide a mounting of the character stated for a seaming head including a reciprocable knockout pad, means for actuating the knockout pad, and novel quick detachable means in the driving connections which may be readily disconnected to permit the swinging away of the seaming head and which can be just as readily again connected to complete the knockout pad driving connections

when the head has been returned to its cooperative relation with the turret.

With the above and other objects in view which will more fully appear, the nature of the invention will be more clearly understood by following the description, the appended claims, and the several views illustrated in the accompanying drawings.

In the drawings:

10 Figure 1 is a vertical longitudinal section through a container assembling machine with the invention embodied thereon.

15 Figure 2 is a fragmentary vertical longitudinal section taken through the axis about which the seaming head is pivotally mounted.

Figure 3 is a detail vertical cross section taken on the line 3—3 on Figure 2.

20 In the container assembling machine hereinbefore referred to and in which the seaming head disclosed is intended for use, there is included a frame base 5 and a frame structure 6 arising therefrom and including a shelf 7 and a vertically disposed bearing sleeve 8.

25 A main power driven shaft 9 is horizontally disposed in suitable bearings in the frame, and a pocketed turret 10 is secured upon one end of a shaft 11 rotatably mounted in a horizontal bearing 12 on the machine frame and equipped at its other end with a disk 13 from which indexing

30 rollers project in equidistantly spaced relation for being engaged by an indexing cam 14 which serves to impart step-by-step rotation to the turret for presenting the pockets thereof at the various stations provided in the machine. The cam 35 14 is mounted on the upper end of a shaft 15 supported in a vertical bearing 16 on the machine frame and driven by a gear couple 17 from a shaft 18 vertically supported in bearings 19 in the frame and in turn driven by a worm gear 40 couple 20 from the shaft 9.

45 Loosely assembled container body end closure elements generally designated 21, when presented at the securing or seaming station at the bottom of the turret as illustrated in Figure 1 of the drawings, are engaged by a chucking pad 22 and are moved thereby from the position illustrated in Figure 1 toward the right for the purpose of engaging the container with the chuck of the seaming mechanism so that the end closure can 50 be seam-secured to the container body in the manner hereinafter described. The chucking pad 22 is adjustably mounted on a slide head 23 reciprocably supported on the frame and having roller connection as at 24 with a grooved plate cam 25 secured upon the upper end of the shaft

18 and through the medium of which the desired reciprocation is imparted to the pad 22.

The seaming head proper, the mounting of which comprises the main subject matter of the present invention, includes upper and lower casting sections 26 and 27 including laterally extended housing portions respectively designated 28 and 29, and these sections 26, 28 and 27, 29 are flange-secured together as at 30. The sections 26 and 27 thus secured form a large open-ended bell portion 31 in which the seaming mechanism 5

proper operates.

A part of the upper portion of the bell 31 is hinge-mounted as at 32 so that it can be swung upwardly to facilitate access to the interior of 15 the bell and the mechanism therein.

A pivot sleeve or standard 33 depends from the lower head section 27, 29, and it will be observed by reference to Figures 1 and 3 of the drawings that the axis of this sleeve is disposed 20 to one side of the axis of the bell portion 31 of the seaming head housing. The housing sections 26, 28 and 27, 29 together provide a bearing hub portion 34 and a bearing hub portion 35 disposed side by side. The pivot standard 33 is pivotally 25 mounted in the bearing sleeve 8 formed on the machine frame, and the weight of the seaming head is supported in this bearing on an anti-friction bearing equipment 36 interposed between the upper end of the bearing sleeve and the opposed portion of said housing.

By reason of the provision of the pivot standard and sleeve bearing equipments 33, 8, it is possible to swing the seaming head housing about the axis of the bearing standard in order to 30 remove the seaming head into and out of cooperative relation with the machine turret so as to facilitate inspection and adjustment of the parts of the seaming mechanism. In order to suitably support the seaming head during swinging thereof between operative and inoperative positions and for avoiding the setting up of twisting strains in the seaming mechanisms in the head, there is provided a supporting lug 37 on the lower head section 27 adapted to be supported upon and ride over an arcuate track 38 extending upwardly from the frame shelf portion 7. A forked lug 39 also projects from the lower housing section and is engageable by a quick detachable pivot screw 40 supported on the machine frame and which may be utilized to secure the seaming head in the operative relation with the turret illustrated in Figure 1 of the drawings.

It will be observed by reference to Figure 2 of the drawings that a shaft member 41 is affixed to the hub 35, and a sleeve 42 is freely rotatable about this shaft within the hub. The sleeve carries a spur gear 43, a slightly larger spur gear 44 and a bevel gear 45. Rotation is imparted to the bevel gear 45 and the sleeve to which it is affixed by a bevel gear 46 affixed upon the upper end of a shaft 47 rotatable in bearings 43 in the standard 33 and which carries a bevel gear 49 at its lower end to which rotation is imparted from a bevel gear 50 secured upon the main drive shaft 9.

The particular seam forming equipments included in the head disclosed in parent case Serial No. 306,366 hereinbefore referred to are particularly adapted to the seaming of square or oblong cans. The particular form of these seaming equipments forms no part of the present invention and it is to be understood that these equipments may be variously formed within the scope of the present invention which relates particu-

larly to the mounting of the seaming head. The seaming equipments are herein generally designated 51 and insofar as the present disclosure is concerned, it will suffice to refer to these equipments as including a stationary chuck 52, a reciprocable knockout pad 53 and a knockout rod 54 for actuating the same, a rotor 55 for carrying the seaming levers, and a rotor 56 for imparting rotation to the cams or other devices for actuating the levers. The rotor 55 has a driving gear 57 affixed thereto and the rotor 56 has a driving gear 58 affixed thereto.

It will be apparent by reference to the drawings that the gears 57 and 58 affixed to the rotors 55 and 56 respectively mesh with and have rotation imparted thereto from the spur gears 43 and 44 respectively which have been hereinbefore referred to as forming a part of the seaming mechanism driving connections.

The knockout rod 54 is extended beyond the seaming head as indicated in Figure 1 and is connected at its extended end with the upper end of a lever 59 pivoted intermediate its ends, as at 60, on a bracket 61 secured to the seaming head hub 34. At its lower end the lever 59 is connected by a quick detachable connection 62 with a link 63 pivoted to a thrust member 64 which is slidable in bearings 65 provided therefor in the machine frame. The thrust member 64 carries a roller 66 which engages a suitably shaped groove in a plate cam 67 which is rotatable with the shaft 18 hereinbefore referred to. The groove in the cam 67 is so shaped, and the rotation of the cam so timed, that the knockout pad 53 and the rod 54 on which it is carried will be actuated at the proper time in each seaming cycle for suitably displacing the seamed container from the chuck 52.

It will be obvious by reference to the drawings 40 that by removing the quick detachable securing screw 40 from engagement with the forked lug 39 the seaming head can be swung about its pivotal mounting 32, 8 whenever it is desirable to remove the head from the cooperative relation 45 with the turret illustrated in Figure 1 of the drawings for the purpose of rendering the mechanisms within the head housing or those mounted on and associated with the turret accessible for adjustment or replacement and the like. This 50 displacement of the head is greatly facilitated by the off-center position of the pivot axis, and the accessibility of the mechanisms within the head are additionally facilitated by the hinge mounting 32 of the upper portion of the housing. 55 Because of the nature of the driving connection between the power shaft 9 and the seaming mechanisms within the head, swinging of the head about its pivotal mounting can be effected without disrupting these driving connections or 60 their synchronized relation to the other mechanisms of the machine. It will be obvious, however, that before the seaming head can be swung away from the turret in the manner above stated, the quick detachable connection 62 forming a 65 part of the knock-out pad operating devices must be released.

It will be apparent also that when the seaming head is swung either out of or into its cooperative relation with the turret 19, the weight of 70 the head is supported by the supporting track equipments 37, 38, thereby to relieve the pivotal mounting of the strain and bending tendency of this off-center weight.

It is to be understood, of course, that the 75 tails of structure and arrangement of parts may

be variously changed and modified without departing from the spirit and scope of the invention.

We claim:

1. In apparatus of the character described, a frame, a horizontally disposed bearing on said frame, a turret rotatably supported in said bearing and including a pocketed disk-like head movable in a vertical plane and adapted to support in its pockets container bodies and end closures in position for being assembled, a chucking pad, means for supporting the pad for reciprocation along a center parallel the turret axis and in line with the path of movement of the turret pockets, means for indexing the turret and reciprocating the pad in timed relation to advance the pad toward a turret pocket each time a pocket comes to rest opposite said pad, a seaming head housing including a large generally circular face portion disposed in a vertical plane closely approximating the plane in which the turret head moves, seaming mechanism in said seaming head and including a chuck aligned with said pad against which a can body and an end closure are pushed by the pad each time the turret comes to rest and power driven can body and end closure seaming devices, a vertically disposed supporting standard projecting from the seaming head, a bearing on said frame for said standard spaced to one side of the turret axis so that the seaming head can be swung about a vertical axis away from the turret to provide a wide space between the turret and said seaming head face portion, a power source on said frame, and driving connections between said power source and the seaming devices and effective to drive said mechanism regardless of the position to which the seaming head is swung.

2. In apparatus of the character described, a frame, a horizontally disposed bearing on said frame, a turret rotatably supported in said bearing and including a pocketed disk-like head movable in a vertical plane and adapted to support in its pockets container bodies and end closures in position for being assembled, a chucking pad, means for supporting the pad for reciprocation along a center parallel the turret axis and in line with the path of movement of the turret pockets, means for indexing the turret and reciprocating the pad in timed relation to advance the pad toward a turret pocket each time a pocket comes to rest opposite said pad, a seaming head housing including a large generally circular face portion disposed in a vertical plane closely approximating the plane in which the turret head moves, seaming mechanism in said seaming head and including a chuck aligned with said pad against which a can body and an end closure are pushed by the pad each time the turret comes to rest and power driven can body and end closure seaming devices, a vertically disposed supporting standard projecting from the seaming head, a bearing on said frame for said standard spaced to one side of the turret axis so that the seaming head can be swung about a vertical axis away from the turret to provide a wide space between the turret and said seaming head face portion, a power source on said frame, driving connections between said power source and the seaming devices and effective to drive said mechanism regardless of the position to which the seaming head is swung, and cooperatively engaging supporting means mounted on the seaming head and the frame respectively in spaced relation to said standard bearing and serving to support said

head in any position to which it is moved about the axis of said standard.

3. In apparatus of the character described, a frame, a horizontally disposed bearing on said frame, a turret rotatably supported in said bearing and including a pocketed disk-like head movable in a vertical plane and adapted to support in its pockets container bodies and end closures in position for being assembled, a chucking pad, 10 means for supporting the pad for reciprocation along a center parallel the turret axis and in line with the path of movement of the turret pockets, means for indexing the turret and reciprocating the pad in timed relation to advance the pad toward a turret pocket each time a pocket comes to rest opposite said pad, a seaming head housing including a large generally circular face portion disposed in a vertical plane closely approximating the plane in which the turret head moves, seaming mechanism in said seaming head 20 and including a chuck aligned with said pad against which a can body and an end closure are pushed by the pad each time the turret comes to rest and power driven can body and end closure seaming devices, a vertically disposed supporting standard projecting from the seaming head, a bearing on said frame for said standard spaced to one side of the turret axis so that the seaming head can be swung about 30 a vertical axis away from the turret to provide a wide space between the turret and said seaming head face portion, a power source on said frame, driving connections between said power source and the seaming devices and effective to drive 35 said mechanism regardless of the position to which the seaming head is swung, said driving connections including a power shaft rotatably supported on the frame beneath and traversing the axis of said standard, a driven shaft vertically rotatable in said standard and bevel gear coupled with said power shaft, and a power transmitting shaft traversing the axis of the driven shaft within said seaming head and bevel gear coupled with said driven shaft.

4. In apparatus of the character described, a frame, a horizontally disposed bearing on said frame, a turret rotatably supported in said bearing and including a pocketed disk-like head movable in a vertical plane and adapted to support 50 in its pockets container bodies and end closures in position for being assembled, a chucking pad, means for supporting the pad for reciprocation along a center parallel the turret axis and in line with the path of movement of the turret pockets, means for indexing the turret and reciprocating the pad in timed relation to advance the pad toward a turret pocket each time a pocket comes to rest opposite said pad, a seaming head housing including a large generally circular face portion disposed in a vertical plane closely approximating the plane in which the turret head moves, seaming mechanism in said seaming head and including a chuck aligned with said pad against which a can body and an end closure 60 are pushed by the pad each time the turret comes to rest and power driven can body and end closure seaming devices, a vertically disposed supporting standard projecting from the seaming head, a bearing on said frame for said standard spaced to one side of the turret axis so that the seaming head can be swung about a vertical axis away from the turret to provide a wide space between the turret and said seaming head face portion, a power source on said frame, driving 65 connections between said power source and the

seaming devices and effective to drive said mechanism regardless of the position to which the seaming head is swung, said driving connections including a driven shaft vertically rotatable in said standard, a power transmitting shaft traversing the axis of the driven shaft within said seaming head and bevel gear coupled with said driven shaft, and a power shaft rotatably supported in the frame and gear coupled with said driven shaft.

5. In apparatus of the character described, a frame, a horizontally disposed bearing on said frame, a turret rotatably supported in said bearing and including a pocketed disk-like head movable in a vertical plane and adapted to support in its pockets container bodies and end closures in position for being assembled, a chucking pad, means for supporting the pad for reciprocation along a center parallel the turret axis and in line with the path of movement of the turret pockets, means for indexing the turret and reciprocating the pad in timed relation to advance the pad toward a turret pocket each time a pocket comes to rest opposite said pad, a seaming head housing including a large generally circular face portion disposed in a vertical plane closely approximating the plane in which the turret head moves, seaming mechanism in said seaming head and including a chuck aligned with said pad against which a can body and an end closure are pushed by the pad each time the turret comes to rest and power driven can body and end closure seaming devices, a vertically disposed supporting standard projecting from the seaming head, a bearing on said frame for said standard spaced to one side of the turret axis so that the seaming head can be swung about a vertical axis away from the turret to provide a wide space between the turret and said seaming head face portion, a power source on said frame, driving connections between said power source and the seaming devices and effective to drive said mechanism regardless of the position to which the seaming head is swung, said seaming mechanism including a reciprocable knockout rod extending through said chuck, and means for actuating said knockout rod from said power source, said last named means including a quick detachable connection for facilitating swinging of said head.

6. In apparatus of the character described, a frame, a horizontally disposed bearing on said frame, a turret rotatably supported in said bearing and including a pocketed disk-like head movable in a vertical plane and adapted to support in its pockets container bodies and end closures in position for being assembled, a chucking pad, means for supporting the pad for reciprocation along a center parallel the turret axis and in line with the path of movement of the turret pockets, means for indexing the turret and reciprocating the pad in timed relation to advance the pad toward a turret pocket each time a pocket comes to rest opposite said pad, a seaming head housing including a large generally circular face portion disposed in a vertical plane closely approximating the plane in which the turret head moves, seaming mechanism in said seaming head and including a chuck aligned with said pad against which a can body and an end closure are pushed by the pad each time the turret comes to rest and power driven can body and end closure seaming devices, a vertically disposed supporting standard projecting from the seaming head, a bearing on said frame for said standard spaced to one side of the turret axis so that the seaming head can be

swung about a vertical axis away from the turret to provide a wide space between the turret and said seaming head face portion, a power source on said frame, driving connections between said power source and the seaming devices and effective to drive said mechanism regardless of the position to which the seaming head is swung, and cooperatively engaging supporting lug and arcuate track equipments carried respectively by said 10 seaming head and said frame in concentrically spaced relation to the supporting standard axis for supporting the head in any position to which it is moved about the axis of said standard.

7. In apparatus of the character described, a 15 frame, a horizontally disposed bearing on said frame, a turret rotatably supported in said bearing and including a pocketed disk-like head movable in a vertical plane and adapted to support in its pockets container bodies and end closures 20 in position for being assembled, a chucking pad, means for supporting the pad for reciprocation along a center parallel the turret axis and in line with the path of movement of the turret pockets, means for indexing the turret and reciprocating 25 the pad in timed relation to advance the pad toward a turret pocket each time a pocket comes to rest opposite said pad, a seaming head housing including a large generally circular face portion disposed in a vertical plane closely approximating the plane in which the turret head moves, 30 seaming mechanism in said seaming head and including a chuck aligned with said pad against which a can body and an end closure are pushed by the pad each time the turret comes to rest and power driven can body and end closure seaming 35 devices, a vertically disposed supporting standard projecting from the seaming head, a bearing on said frame for said standard spaced to one side of the turret axis so that the seaming head can be swung about a vertical axis away from the turret to provide a wide space between the turret and said seaming head face portion, a power source on said frame, driving connections between said power source and the seaming 40 devices and effective to drive said mechanism regardless of the position to which the seaming head is swung, said driving connections including a power shaft rotatably supported on the frame beneath and traversing the axis of said standard, 45 a driven shaft vertically rotatable in said standard and bevel gear coupled with said power shaft, a power transmitting shaft traversing the axis of the driven shaft within said seaming head and bevel gear coupled with said driven shaft, said 50 seaming mechanism also including a seaming lever carrying rotor and a seaming lever actuating rotor, a spur gear on each said rotor within the head, and spur gears on said power transmitting shaft and meshing with the spur gears on said 55 rotor.

8. In apparatus of the character described 60 wherein is provided a turret rotatable in a vertical plane about a horizontal axis, a frame, a chucking pad horizontally reciprocable on said frame, a seaming head housing having an open end placed in a vertical plane in close parallel spaced relation to the plane in which said turret rotates and having seaming mechanism therein including a chuck opposing said chucking pad, 65 bearing having its axis disposed vertically to one side of the vertical plane in which the turret axis lies, a supporting standard depending from the housing and pivotally mounted in said bearing whereby said housing can be swung away 70 from the turret to provide a wide opening be- 75

tween the turret and said housing open end, a source of power, and driving connections between said power source and the seaming mechanism within said housing and effective to drive said mechanism regardless of the position of said housing.

9. In apparatus of the character described wherein is provided a turret rotatable in a vertical plane about a horizontal axis, a frame, a chucking pad horizontally reciprocable on said frame, a seaming head housing having an open end placed in a vertical plane in close parallel spaced relation to the plane in which said turret rotates and having seaming mechanism therein including a chuck opposing said chucking pad, bearing having its axle disposed vertically to one side of the vertical plane in which the turret axis lies, a supporting standard depending from the housing and pivotally mounted in said bearing whereby said housing can be swung away from the turret to provide a wide opening between the turret and said housing open end, a source of power, driving connections between said power source and the seaming mechanism within said housing and effective to drive said mechanism regardless of the position of said housing, and cooperatively engaging supporting lug and articulate track equipments carried respectively by said seaming head housing and said frame in concentrically spaced relation to the supporting standard for supporting the seaming head housing in any position to which it is moved about the axis of said standard.

10. In apparatus of the character described wherein is provided a turret rotatable in a vertical plane about a horizontal axis, a frame, a chucking pad horizontally reciprocable on said frame, a seaming head housing having an open end placed in a vertical plane in close parallel spaced relation to the plane in which said turret rotates and having seaming mechanism therein including a chuck opposing said chucking pad, bearing having its axis disposed vertically to one side of the vertical plane in which the turret axis lies, a supporting standard depending from the housing and pivotally mounted in said bearing whereby said housing can be swung away from the turret to provide a wide opening between the turret and said housing open end, a source of power, driving connections between said power source and the seaming mechanism within said housing and effective to drive said mechanism regardless of the position of said housing, said driving connections including a power shaft rotatably supported on the frame beneath and traversing the axis of said standard, a driven shaft vertically rotatable in said standard and bevel gear coupled with said power shaft, and a power transmitting shaft traversing the axis of the driven shaft within said housing and bevel gear coupled with said driven shaft, said power transmitting shaft having its axis disposed parallel and beside the axis of the housing.

ALFRED L. KRONQUEST.
